UNITED STATES PATENT OFFICE.

LOUIS SCHLESINGER AND HERMAN E. HEINE, OF MILWAUKEE, WISCONSIN, AS
SIGNORS TO BRADLEY WASHFOUNTAIN COMPANY, OF MILWAUKEE, WISCONSIN, A
CORPORATION OF WISCONSIN.

VALVE.

Application filed November 21, 1925. Serial No. 70,556.

This invention relates to valves more particularly although not solely adapted for use in connection with sanitary wash fountains or lavatories.

5 It is the present day practice in modern factories and other buildings in which large numbers of persons are employed to provide lavatories for washing purposes.

These lavatories are usually of circular 10 shape to permit a number of persons to wash at the same time and are provided with valves for controlling the flow of water. The valves are usually positioned on one side of the lavatory and if a person washing on the 15 side of the lavatory opposite to the side provided with the valve desires to turn the water off or on, it is necessary to walk around the fountain with the result that the valve is often left in the on position and considerable water 20 is wasted.

It is one of the objects of the present invention to in part overcome the before mentioned objectionable features and provide a valve member having two valves with stems projecting in opposite directions to permit turning either valve to on or off position.

A further object of the invention is to provide a valve which is of simple construction, is strong and durable and is well adapted 30 for the purpose described.

With the above and other objects in view the invention consists of the improved valve and its parts and combinations as set forth in the claim, and all equivalents thereof.

35 In the accompanying drawing in which the same reference characters indicate the same parts in all of the views,

Fig. 1 is a side view of the improved valve shown having a supply and a discharge pipe 40 connected thereto.

Fig. 2, is a central vertical sectional view therethrough; and

Fig. 3, is a side view of a wash-fountain with the improved valve connected thereto 45 to indicate its use.

Referring to the drawing the numeral 5 indicates a valve casing which is formed with an upper inlet opening 6 and a lower outlet opening 7. The casing is also provided with 50 opposite chambers 8 for receiving opposite

valves 9 therein. The inlet portion of the casing is provided with a depending partition 10 of less diameter than the bore 11 of the casing to form a space between the partition and the inner walls of the casing as clearly 55 shown in Fig. 2. The bore 12 of the inlet portion of the casing extends into the depending partition 10 and is formed with opposite ports 13, which are in alinement with the valves 9 and connect the valve spaces 8 with the bore 12. The depending partition is also formed with outwardly projecting annular valve seats 10' surrounding the ports 13 which seats are engaged by the disk valves 9 to close said ports as desired. Said valves 60 are formed with threaded portions 13' which engage the threaded portions 14' of the casing 5. Valve stems 14 forming part of the valves 9 extend outwardly through the casing and at their outer end portions have 65 handles 15 mounted thereon for convenience in moving the valves to and from their seats. Cap members 16 surround the valve stems and are threaded to the casing to permit 70 assembling the parts together and said cap 75 members are provided with stuffing nuts 17 to prevent the escape of water around the valve stems 14.

The valve chambers 8 are in communication with the bore 11 of the casing, so that when 80 one of the valves 9 is turned to open position water will flow from the supply pipe 18 through the valve and into the pipe 19.

The valve is particularly adapted for use with a washfountain 20 as shown in Fig. 3. 85

From the foregoing description it will be seen that the valve is of very simple construction and that users of a washfountain provided with the valve member having oppositely extending valve stems can control the 90 flow of water from either side of the fountain.

What we claim as our invention is:

A valve, comprising a casing having an upper inlet opening and an alined lower outlet opening and opposite side threaded openings 95 in alinement with each other, all of said openings being alined in a vertical plane, said casing also having a depending central partition of less diameter than the bore of the casing to form a space between the two parts, 100

said partition provided with opposite ports in alignment with the threaded openings and opening communication between the inlet opening and the outlet opening, and valves for controlling said ports and having threaded portions engaging the threaded portions of the casing, said valves also having stems which extend outwardly through the opposite threaded portions of the casing and have handles on their outer ends. 10

In testimony whereof, we affix our signatures.

LOUIS SCHLESINGER.
HERMAN E. HEINE.
